UNITED STATES PATENT OFFICE.

JOSEPH C. WHITE, OF CHELSEA, MASSACHUSETTS, ASSIGNOR TO JAMES E. MAYNADIER, TRUSTEE, OF BOSTON, MASSACHUSETTS.

FIREARM.

SPECIFICATION forming part of Letters Patent No. 717,958, dated January 6, 1903.

Application filed September 13, 1899. Serial No. 730,358. (No model.)

To all whom it may concern:

Be it known that I, JOSEPH C. WHITE, of Chelsea, in the county of Suffolk and State of Massachusetts, have invented a new and useful Improvement in Firearms, of which the following is a specification.

My invention is an improvement on the combined pistol and knife described in my Patent No. 626,472, dated June 6, 1899; and it consists in a novel lock and novel means for cocking the gun, as fully described below and specifically claimed.

Figure 1 is an elevation, partly in section, of one form of my invention. Fig. 2 is an edge view of the article shown in Fig. 1. Fig. 3 shows the trigger detached. Fig. 4 is a detail of the firing-plunger. Fig. 5 is a section on line 5 5 of Figs. 1 and 2, and Fig. 6 is a detail hereinafter referred to.

In the drawings, A, B, and C represent three plates of substantially the same shape, and between the plates A and B are located the barrel D and the lock or firing mechanism, and between the plates B and C is located the knife-blade E. The barrel D and knife-blade E are both pivoted upon a bolt d', so that the blade E may be swung into its open position in the usual manner and so that the breech of the barrel D may be swung out from between the plates A and B to a limited extent, as shown by dotted lines in Fig. 6, in order that a cartridge may be inserted or a shell extracted.

The breech-block F supports the side plates A and B and the back plate G, which is secured at its other end to the block H by means of the screw g'. The block H is formed with a threaded socket in which is fitted the threaded end of a rod I, and the opposite end of the rod I is secured in a socket in the breech-block F by means of a screw f'. The rod I guides the firing-plunger J, which is moved lengthwise on the rod I in one direction by hand and in the opposite direction by the spring j, which bears at one end against the breech-block F and at its opposite end against the firing-plunger.

To one end of the firing-plunger J is pivoted at j' a finger-piece j'', which lies within a slot g'' in the back plate G and has a projection

extending outside of the stock, which when moved to the rear by the finger turns the finger-piece on its pivot j', so that it may be grasped by the hand. (See Fig. 6.) The finger-piece is then moved to the rear by the hand, and with it the firing-plunger J on its guide I into the firing position. When inoperative, the finger-piece j'' lies within the stock, as shown in Fig. 1.

The firing-plunger J is notched, as at j''' j'', and these notches are engaged by the free end of a spring-sear j'', which is secured to the back plate G by rivets g''. When the firing-plunger J is in its firing position, as shown in Fig. 6, notch j''' is engaged by spring-sear j''. To fire the pistol, the sear j'' is moved out of engagement with the notch j''' by means of the trigger K, which is pivoted on a pin k, fast on the plate B. The inner end of the trigger K is formed with a slot k', into which extends a projection j'' on the free end of the sear j''. The part k'' of the trigger K, which is located at one side of the slot k', is yielding, so that as the firing-plunger J is drawn back by hand the part k'' will yield as the free end of the sear j'' rides along the firing-plunger.

On the rod I is a split washer i'', the ends of which are separated, and said washer is located between the end of the firing-plunger J and the check-nut i and serves as a yielding abutment against which the end of the firing-plunger strikes and to return the firing-plunger to its half-cocked position. (Shown in Fig. 1.)

The firing-plunger J is provided with an offset or projection j'', which engages the cartridge in the barrel D when the plunger J is thrown forward by the spring j.

The barrel D is notched on one side at d'' for the spring-catch d'', which is secured to the breech-block F by the screw d''. This notch and catch serve to lock the barrel D in its closed position. The catch d'' is thrown out of the notch d'' by the pin d'', which is mounted in a socket in the breech-block F and extends through the plate A to the outer side thereof.

The pin k, on which the trigger K is pivoted, extends through a slot k''' in said trigger, and a portion k'' of the trigger K projects

through the slot g^4 in the back plate G and is formed of a convenient shape to be engaged by the thumb of the operator, and a notch k^3 is formed in the trigger K at that end which is normally held by a spring k^4 , located between the block H and trigger K, in engagement with one end of the slot g^4 in the back plate G, as shown in Fig. 6, so that in order to disengage trigger K from the back plate G the trigger must be moved bodily against the force of the spring k^4 until the notch k^3 is moved out of engagement with the back plate G, and when this has been done the trigger K may be swung on the pin k to disengage 15 sear j^5 from the firing-plunger J and the latter released. The trigger is normally locked in a fixed position and cannot be moved to release the firing-plunger without first disengaging it from the back plate, and accidental discharge of the piece is thus prevented.

What I claim as my invention is—

1. In a firearm the lock above described, comprising a firing-plunger; its spring; a notch in the plunger to receive a yielding sear; that sear; and a trigger with a slot receiving a projection from the sear, and with one wall of the slot yielding to allow motion 25

of the sear as the notch in the plunger forces the engaging end of the sear to one side.

2. In a firearm the combination of a firing-plunger bored longitudinally; a fixed rod extending through that bore; a spring to throw the plunger forward on that rod; means for moving the plunger on that rod against the force of the spring; a sear for retaining the 30 plunger when in its cocked position; and a trigger for releasing the sear from engagement with the plunger.

3. In a firearm the combination of a firing-plunger; a spring for that plunger; means for 40 moving the plunger against the force of the spring; a sear for locking the firing-plunger; a back plate; a trigger movable endwise and slotted to engage the back plate; a spring to hold the trigger-slot in engagement with the 45 back plate and thereby prevent the trigger from being tilted to release the sear until after the trigger has been moved endwise and its slot released from the back plate.

JOSEPH C. WHITE.
